MAGNIFYING DEVICE

Alice B. Ridabock, Stamford, Conn.

Application October 16, 1935, Serial No. 45,202

4 Claims. (Cl. 88—39)

This invention relates to magnifying apparatus.

One of the objects of this invention is to provide magnifying apparatus which will be simple, practical and thoroughly durable. Another object is to provide a construction of the above character which may be made from inexpensive materials and whose manufacture is free from complication and detail work. Another object is to provide a construction of the above character which will be neat and attractive in appearance and yet be of such sturdy construction as to withstand hard usage. Another object is to provide a construction of the above character which may be easily manufactured at a minimum cost. Another object is to provide a construction of the above character which may be supported by the body of the user and which does not interfere with the movement of the hands. Another object is to provide a construction of the above character in which the distance between the eyes of the user and the lens may be readily and permanently adjusted. Other objects will be in part apparent and in part pointed out hereinafter.

The invention accordingly consists in the features of construction, combination of elements, and arrangements of parts as will be exemplified in the structure to be hereinafter described and the scope of the application of which will be indicated in the following claims.

30 In the accompanying drawing in which is shown one of the various embodiments of my invention,

Figure 1 is a perspective view of my device shown in its relation to the body of a user;

Figure 2 is a top plan view having the cover members in an open position;

Figure 3 is a vertical sectional view taken along line 3—3 of Figure 2;

Figure 4 is a vertical sectional view taken along line 4—4 of Figure 2;

Figure 5 is a top plan view having the cover members in a closed position;

Figure 6 is a top plan view of a part of the construction shown in Figure 1, and Figure 7 is a vertical sectional view taken along line 7—7 in Figure 6.

Similar reference characters refer to similar parts throughout the several views of the drawing.

Referring now to the drawing in detail, there is shown in Figure 2, a support generally indicated at 10 having a lens 11 mounted therein. Support 10 preferably is comprised of two plates 12 and 13, as is more clearly shown in Figure 4, which are stamped from sheet metal having holes 14 and 15 formed therein. Preferably the sheet

metal tapers to a knife edge around the periphery of holes 14 and 15. These tapered portions around the peripheries of holes 14 and 15 extend upwardly out of the planes in which the main portions of the plates lie. Thus when the plates 5 are placed together, as in Figure 4, so that the tapered portions thereof around holes 14 and 15 extend away from each other, a track 16 is formed.

Lens 11 which has a diameter greater than the 10 diameter of holes 14 and 15 is placed between plates 12 and 13 so that its periphery lies in track 16. Tapered portions 17 and 18 (Figure 4) because of their outward flange fit the concave sides of the lens and because of their tapered 15 edge form a neat and attractive connection therebetween. Plates 12 and 13 are then secured together by any suitable means such as spot soldering their outer edges thus securely mounting lens 11 within support 10. Support 10 is preferably 20 so shaped that the distance between the inner edges of holes 14 and 15 and edge 19 of support 10 is great enough to support lens 11 a substantial distance outwardly from the body of the user. Thus I have provided a lens securely mounted in 25 a support, the support being so shaped that if its inner edge 19 is placed upon the body of the user and held in position substantially perpendicular thereto, it is held outwardly a sufficient distance to permit the user to view work held thereunder 30 in the hands.

Pivots secured to the inner corners 50 and 51 of support 10 (Fig. 2) are cover members generally indicated at 20 and 21. As cover members 20 and 21 are substantially similar in construction, I will limit my description to cover member 21. Referring now to Fig. 3, cover member 21 is preferably stamped from a single plate of sheet metal forming a pair of sides 22 and 23 and an end wall 24 (Figs. 3 and 5). Preferably cover 21 40 is so shaped that its upper portion covers half of lens 11 (Fig. 5) and end wall 24 lies outside of edge 19 of support 10. Furthermore, sides 22 and 23 curve outwardly below the lens 11 to leave an exposed portion 53 of support 10 when they 45 are in a closed position. End wall 24 preferably terminates short of the ends 25 and 26 of sides 22 and 23 forming a pair of ears 27 and 28. Ears 27 and 28 preferably extend over opposite sides of corner 51 (Fig. 2) and are pivotally secured 50 thereto by rivets 29. Preferably between the inner surface of ears 27 and 28 and the outer surface of plates 12 and 13, I have placed a pair of washers 30 and 31 which prevent friction between sides 22 and 23 and support 10 thus al- 55

lowing freer movement of the cover member. As sides 22 and 23 are spaced by wall 24, a space is left between the sides and as ears 27 and 28 extend over opposite sides of support 10, cover member 21 may be turned on its pivotal connection so that in view of the shape of the cover member half of lens 11 is covered. Thus cover members 20 and 21 when in a closed position cover lens 11 protecting it from damage when the device is not in use and also with support 10 form a neat and compact unit.

Preferably pivots 29 and 32 are so placed that edges 54 and 55 form a continuous edge with the end 19 of support 10 (Fig. 2) when the device is in an open position. Preferably rivets 29 and 32 are sufficiently tight to cause some friction between the washers and the support 10 so that when adjusted they retain their position with relation to support 10. Thus the user may adjust the continuous edge formed by edges 55, 54, and 19 to any desired shape to fit the contour of his or her body by moving cover members 20 and 21 about their pivots.

Adjacent the inner edge of lens 11 within exposed portion 53 (Fig. 5) and extending through support 10 I have formed two holes 33 and 34 through which cord 35 is preferably looped. Referring now to Fig. 1, cord 35 is preferably of sufficient length to extend upwardly around the neck of the user and has a device 36 secured therein for adjusting its length. Adjusting device 36 (Figures 1, 6 and 7) may be of any desired construction but preferably consists of a metal plate 70 having two holes 70a and 70b formed therein. The diameter of holes 70a and 70b is preferably substantially the same as the diameter of cord 35. Cord 35 passes through holes 70a and 70b to form a loop 71, the size of which is readily variable to adjust the length of cord 35. The angle at which the cord extends through the plate retains any adjustment that is made. Thus the cover members may be opened and adjusted to fit the contour of the body, cord 35 may be placed about the neck of the user and by adjusting device 36 lens 11 may be placed at any desired distance from the eyes of the user.

The point of attachment of the cord is preferably such that the device will tend to swing by gravity toward the body and be held against tilting by its contact therewith. Thus in work such as knitting with a very fine yarn which places an undesirable strain upon the eyes of the worker, the user may adjust the device, as shown in Fig. 1, and easily accomplish the work as it is greatly magnified. Thus I have provided a device which greatly reduces the strain of working on work of small detail and which allows complete freedom of the hands for accomplishing this work. Furthermore, the device has been so constructed that its cover members enclose it to form a neat and compact unit while at the same time they perform the useful objects of protecting the lens when in a closed position and forming an adjustable body support when in an open position.

It will thus be seen that I have provided a thoroughly practical and efficient magnifying apparatus in which the several objects hereinabove mentioned as well as many others are successfully accomplished.

As many possible embodiments may be made of the above invention and as many changes might be made in the embodiment above set forth, it is to be understood that all matter hereinbefore set forth, or shown in the accompanying drawing, is to be interpreted as illustrative and not in a limiting sense. 5

I claim:

1. In magnifying apparatus, in combination, a magnifying lens, a support for said magnifying lens, a pair of arms pivotally connected to said support and being adapted to swing relative thereto and to each other to close over said lens and outwardly into an open position forming means for adjusting the relation between said support and the body of the user, flexible means secured to said support, said means being adapted to be attached to the body of the user, and means for adjusting the length of said flexible means whereby the lens may be moved toward and away from the eyes of the user.

2. In magnifying apparatus, in combination, a magnifying lens, a support for said magnifying lens, closure members pivotally connected to said support, said closure members being adapted to serve both as covers for said lens and as braces for said support, and adjustable means secured to said support, said adjustable means being adapted to be connected to the body of the user, whereby the distance between said lens and the eyes of the user may be varied, said adjustable means being so connected to said support that said lens lies in substantially parallel planes as it is moved toward and away from the eyes of the user.

3. In magnifying apparatus, in combination, a magnifying lens, a supporting device upon the outer portion of which said lens is mounted, said supporting device comprising an inwardly extending member having an inner portion shaped to engage the forward portion of the body of the user and to contact the same along a line of such length as to resist lateral swinging of the member and a suspending device secured to said supporting member at a point inward from the lens and extending upwardly about the upper portion of the body of the user adapted to prevent said lens from tilting downwardly as said first device prevents it from swinging inwardly or laterally.

4. In magnifying apparatus, in combination, a magnifying lens, a supporting device upon the outer portion of which said lens is mounted, said supporting device comprising an inwardly extending member having an inner portion shaped to engage the forward portion of the body of the user and to contact the same along a line of such length as to resist lateral swinging of the member and a suspending device secured to said supporting member at a point inward from the lens and extending upwardly about the upper portion of the body of the user adapted to prevent said lens from tilting downwardly as said first device prevents it from swinging inwardly or laterally, said suspending device comprising a flexible member extending about the neck of the user and adapted to be adjusted in effective length.

ALICE B. RIDABOCK.
